3,074,092 HOLDER FOR YARN MOPS

Herbert A. Siemund, Skokie, Ill., assignor to Greenview Manufacturing Company, Chicago, Ill., a corporation of Illinois

Filed Oct. 18, 1961, Ser. No. 145,868
4 Claims. (Cl. 15—150)

The present invention relates generally to yarn mops, and it has particular relation to a mechanical handle receiving socket holder for clamping the yarn mop therein.

Heretofore, there have been many different types of holders for yarn mops, including holders wherein the two clamping elements are bolted or otherwise secured removably together, which frequently requires the use of tool for assembling and disassembling. Other types have spring pressed clamping elements, which if the spring tension is too weak, fail to clamp the yarn mop head securely therein, and, if the tension is too great, the operator frequently does not have the strength to assemble and disassemble the unit with the yarn mop therein.

There has been provided with the present invention a simple, durable and inexpensive yarn mop holder that is not only devoid of screws, nuts and/or bolts, but also devoid of any spring pressed clamping elements which require considerable force to move or remove from locking position. In other words, this invention provides a mechanical mop holder for a yarn mop head that will securely clamp and/or release the same without the use of tools or force, whereby anyone even a small child could operate the same without difficulty.

An object of the present invention is to provide a simple, durable and inexpensive holder for yarn mops that is easy to manipulate for inserting and/or removing the yarn mop head.

Another object of the invention is the provision of a holder for yarn mops that has a single movable part for securing and/or releasing the yarn mop head therefrom, which is devoid of any screws, nuts and/or bolts or any spring pressing and/or spring urging members requiring tools or force to manipulate the same.

Other and further objects and advantages of the invention, which result in simplicity, economy and efficiency, will be apparent from the following detailed description, reference being had to the accompanying drawings, forming a part hereof, wherein like numerals indicate like parts, in which:

FIGURE 1 is a fragmentary front elevational view of an assembled yarn mop embodying the principles of the invention;

FIGURE 2 is a fragmentary side elevational view of the yarn mop shown in FIGURE 1 with the frame in cross-section, but on a slightly different scale;

FIGURE 3 is a fragmentary view of the mop assembly shown in FIGURE 1 with its yarn mop head removed and its pivotal wedging member in its open or loading position; and

FIGURE 4 is an enlarged longitudinal sectional view, taken substantially along the line 4—4 of FIGURE 3, looking in the direction of the arrows.

Referring now to FIGURE 1, there is shown a metal yarn mop holder consisting of a slightly tapered handle receiving socket member 11, adapted to receive removably a wooden handle member 12, having a fixed mop head supporting member 13 consisting of spaced arms 15 and 16 projecting outwardly from one side, and a pivotal mop head wedging member 17 projecting outwardly from the opposite side between which is secured removably a conventional yarn mop head 18 when said members are juxtaposed or centered on the longitudinal axis of the receiving member 11.

The tapered handle receiving socket member 11 is

2

made up of two sheet metal sections 19 and 21, stamped in the cross-sectional form of a semi-circle and having oppositely extending diametrical flanged edges 22 and 23. The flanged edges 22 and 23 are permanently secured together by any suitable means, as for example, spot-welds (not shown), to provide a hollow handle receiving socket member 11, having an open top into which a wooden handle 12 may be fitted frictionally for manipulating the same.

Below the hollow handle receiving socket, as best shown in FIGURES 1 and 4, each section 19 and 21 is spaced and provided with an integral flange plate 26 and 27, respectively. The flange plates 26 and 27 each has an axial boss 28, which is circular in shape (see FIGURE 4). Each boss 28 is apertured axially, as indicated at 29, for receiving a shaft. The flange plates 26 and 27 each has an outwardly turned flange edge 31 and 32, respectively, extending around the lower half of their peripheries. Each flange edge 31 and 32 is notched or grooved in line with the vertical axis of the socket member 11, as indicated at 33. The flange plates 26 and 27 are adjacent along one side and along one-half of their bottom edges, which, in the drawings, is the left side and left bottom, but are spaced along the opposite side 25 and along the opposite bottom edge, as best indicated at 34 in FIGURE 2. The space 34 extends from the axis of the flange plates 26 and 27 along the lower right quadrant to the longitudinal axis of the socket member 11, and is of a width to provide a space for pivoting 30 the securing wedge member 17 therebetween, as will hereinafter be more fully described.

The mop supporting member 13 consists of a single rod suitably bent to provide spaced arms 15 and 16, which are integrally connected at the free outer end 20 35 in a loop of one hundred and eighty degrees. The opposite ends of each arm 15 and 16 are looped, as indicated at 41 and 42 (see FIGURE 4), to encircle their respective bosses 28. A section of each arm 15 and 16 adjacent the loops 41 and 42, as indicated at 43, 40 is straight and extends along an axis parallel to the longitudinal axis of the socket member 11 and through the notches 33, which serve to lock said member in a fixed vertical position in line with the handle member 11. The arms 15 and 16 have an intermediate section 45 bent outwardly at an obtuse angle or at an angle that is substantially diagonal to the longitudinal axis of the holder, as indicated at 44. The lower end section 46, which actually supports the yarn mop head 18, is bent substantially inwardly at right angles to the intermediate 50 sections, as indicated at 47. The section 46 is slightly arcuate but projects along substantially a horizontal plane, as best shown in FIGURES 1 and 3, that extends and crosses transversely of said longitudinal axis.

The pivotal securing or wedging member 17 consists 55 of a single rod having its inner end bent into a loop, as indicated at 51. The looped end 51 is mounted between the flange plates 26 and 27 and over a bearing member 53, which, in turn, is mounted on a shaft 52. The shaft 52 is positioned through the apertures 29 in the bosses 60 28 of said flange plates 26 and 27. The adjacent side and bottom sections of the flange plates 26 and 27 prevent the pivotal member 17 from pivoting clockwise beyond the vertical in such direction, but the space 34 along the opposite side and bottom quadrant permits 65 pivoting through an arc of ninety degrees in a counter-clockwise direction, which in the drawings is from left to right. The shaft, which is shown in the form of a bolt 52, is threaded at one end, as indicated at 54, for receiving a locking nut 55. The wedging member 17 is mounted oppositely to the supporting member 13 on the shaft 52, but obviously this is only a matter of choice as both could be mounted in the same manner, if desired.

The wedging member 17 has a similar straight section 56, a shorter but similar intermediate section 57 and a corresponding arcuate outer end section 58, whose extreme outer free end 59 has been turned upwardly to prevent its catching in the strands of the yarn mop 18 when being moved into its locking position.

It will be apparent that the supporting member 13 and the wedging member 17 must be spaced vertically a distance slightly less than the thickness of the yarn mop head 18 to be secured therebetween. While, in the drawings, the supporting member 13 is shown to be the longer of the two members, it will be obvious that the wedging member 17 could be made to swing below the supporting member 13 instead of above the same without departing from the spirit of the invention. Manifestly, the shape of the supporting member 13 and the shape of the pivotal wedging member 17 need not be limited to that shown in the drawing, but other shapes may be used which will wedgingly hold a yarn mop head removably therebetween.

In assembling the holder 11, the looped ends 41 and 42 are positioned on their respective bosses 28, the looped end 51 of the wedging member 17 has its bearing member 53 inserted therein, and it is then positioned between the spaced flange plates 26 and 27 with its loop in horizontal alignment with the axial apertures 23 in the spaced bosses 28. A hub cap 62 is mounted over the boss 28 and the encircling loop 41 of the arm 15 on the boss 28 of the flange plate 26. The shaft bolt 52 may now be inserted through the aligned apertures until its threaded end 54 projects beyond the boss 28 of the flange plate 27. Then a hub cap 63 is mounted over the projecting end of the shaft 52 and over the boss 28 and the encircling loop 42 of the arm 16 on the flange plate 27, whereupon a locking nut 55 is threaded onto the projecting threaded end 54 of the shaft 52. The nut 55 is then tightened sufficiently to pull the assembly together while leaving the wedging member 17 free for manual pivoting transversely of the longitudinal axis of the holder and in the plane of the fixed member 13.

When it is desired to insert or remove a yarn mop head 18 from the assembly, it is only necessary to pivot the wedging member 17 to the counterclockwise position shown in FIGURE 3, whereupon the yarn mop head 18, supported by the spaced arms 15 and 16 of the supporting member 13, may be replaced. By merely pivoting the wedging member 17 back clockwise to the vertical position shown in FIGURE 1, the yarn mop head 18 is again locked into its mopping position.

Although I have shown and described in detail only one form which the invention may assume, it will be readily apparent to those skilled in the art that many modifications may be made therein without departing from the spirit thereof or from the scope of the appended claims.

What I claim is:

1. An elongated holder for yarn mops having a socket member open at its upper end for receiving a handle and having spaced fixed and pivotal supporting members of different lengths depending from its lower end,

(a) said fixed member projecting downwardly and outwardly of said socket member at an angle substantially diagonally to the longitudinal axis of said holder and having a lower section projecting inwardly and transversely across said axis,

(b) said pivotal member projecting downwardly and outwardly of said socket member at an angle substantially diagonally to the longitudinal axis of said holder and having a lower section projecting inwardly and transversely across said axis,

(c) said pivotal member being movable transversely of the longitudinal axis of said holder and in the plane of said fixed member, and

(d) said transversely extending lower sections of said members when in clamping position extend in different substantially horizontal planes spaced ver-

4
tically a distance slightly less than the thickness of the yarn mop to be secured therebetween.

2. An elongated holder for yarn mops having a socket member open at its upper end for receiving a handle and having spaced fixed and pivotal supporting members of different lengths depending from its lower end,

(a) said fixed member projecting downwardly and outwardly to one side of said socket member at an angle substantially diagonally to the longitudinal axis of said holder and having a lower section projecting inwardly and transversely across said axis,

(b) said pivotal member projecting downwardly and outwardly to the opposite side of said socket member at an angle substantially diagonally to the longitudinal axis of said holder and having a lower section projecting inwardly and transversely across said axis,

(c) said pivotal member swingable transversely of the longitudinal axis of said holder and in the plane of said fixed arm,

(d) said transversely extending lower sections when in clamping position extend in different substantially horizontal planes spaced vertically a distance slightly less than the thickness of the yarn mop to be secured therebetween.

3. A holder for yarn mops having a socket member open at its upper end for receiving a handle and having spaced fixed and pivotal L-shaped supporting arms of different lengths depending from the lower end,

(a) said L-shaped fixed arm consisting of spaced parallel rods projecting downwardly and outwardly to one side of said socket member at an angle substantially diagonally to the longitudinal axis of said holder and having a lower section consisting of spaced parallel rods projecting inwardly and transversely across said axis,

(b) said pivotal L-shaped arm consisting of a single rod projecting downwardly and outwardly to the opposite side of said socket member at an angle substantially diagonally to the longitudinal axis of said holder and having a lower section projecting inwardly and transversely across said axis,

(c) said pivotal arm being movable transversely of the longitudinal axis of the holder and in the plane of said fixed arm,

(b) said transversely extending lower sections when in clamping position extend in different substantially horizontal planes spaced vertically a distance slightly less than the thickness of the yarn mop to be secured therebetween, and

(e) said lower free end section of said pivotal arm when in mop holding position extending in vertical alignment with the space between said parallel rods of said lower free end section of said fixed arm.

4. A holder for yarn mops having a socket member open at its upper end for receiving a handle and having spaced fixed and pivotal L-shaped supporting arms of different lengths depending from its lower end,

(a) said L-shaped fixed arm projecting downwardly and outwardly to one side of said socket member at an angle substantially diagonally to the longitudinal axis of said holder and having a lower section projecting inwardly and transversely across said axis,

(b) said pivotal L-shaped arm projecting downwardly and outwardly to the opposite side of said socket member at an angle substantially diagonally to the longitudinal axis of said holder and having a lower section projecting inwardly and transversely across said axis,

(c) said pivotal arm being movable laterally of the longitudinal axis of said holder and in the plane of said fixed arm,

- (d) means for limiting the pivotal movement of said pivotal arm, and
- (e) said transversely extending lower sections when in clamping position extend in different substantially horizontal planes spaced vertically a distance slightly less than the thickness of the yarn mop to be secured therebetween.
